UNITED STATES PATENT OFFICE.

CASWELL T. CHESHIER, OF TRENTON, MISSOURI, ASSIGNOR OF ONE-HALF
TO ALBERT L. CHESHIER, OF SAME PLACE.

FURNACE-DOOR.

SPECIFICATION forming part of Letters Patent No. 247,614, dated September 27, 1881.

Application filed May 23, 1881. (No model.)

To all whom it may concern:

Be it known that I, CASWELL T. CHESHIER, of Trenton, in the county of Grundy and State of Missouri, have invented certain new and useful Improvements in Furnace-Doors for Locomotive-Engines; and I do hereby declare that the following is a full, clear, and exact description of the invention, which will enable others skilled in the art to which it appertains to make and use the same, reference being had to the accompanying drawings, which form a part of this specification, in which—

Figure 1 is a perspective view of so much of the interior of the cab of a locomotive as is necessary to illustrate my invention. Fig. 2 is a bottom plan of the floor of the cab—*i. e.*, a plan of the under side of the floor; and Fig. 3 is a detail view of the treadle and its curved connecting-rod or pitman detached.

Similar letters of reference indicate corresponding parts in all the figures.

My invention has relation to means for opening and closing the furnace-doors of locomotive-engines; and it consists in the combination, with the door, of a mechanism which is located underneath the floor of the cab and operated by a treadle in the floor, substantially as and for the purpose hereinafter more fully described.

In firing a locomotive-engine it is of importance to keep the furnace-door closed as much as possible, in order to keep the draft from entering the fire-box through the door; and it is the object of my invention to enable the fireman to open and shut the door by operating a treadle placed in the floor of the cab with his foot, so that he need not let go of the shovelful of coal he is about to shovel into the furnace while opening the door, while at the same time the door will shut of itself the moment the engine is fired and he lets go of the treadle with his foot.

In the annexed drawings, A represents the floor, and B the front side of the cab, facing the boiler. C is the door, which may be of any desired make or construction, and is provided with a pivoted latch-bar, *a*, and parallel arms *b b*, secured at their outer ends in the upright post or pintle D, which works in the brass boxes shown at *c c c*, arranged in a vertical line

with one another, and two of which project into the cab, while the lowermost box is underneath its floor.

The outer end of the latch-bar *a* projects, when the door is closed, into the spring-latch, 55 composed of a rigid lower lip, *d*, and an upper flexible lip or spring, *e*, the lower lip, *d*, being made inclined or slanting and bent downward at its outer end to permit the latch-bar to enter the latch freely when the door is closed. At 60 the inner end of the latch the space or recess between the two parts *e* and *d* is square or rectangular, without any slant, so that the latch-bar will bind between the parts *d* and *e* by the downward spring-pressure of the latter. 65

The lower end of the post or pintle D, below the floor, has a short arm, *f*, at right angles, in the outer end of which is pivoted another arm, *E*, which connects it with the short arm of a lever, *F*, having its fulcrum in the bearing- 70 plate *G*, bolted to the under side of the cab-floor. The other end of lever *F* is connected on one side to the jointed arm *G'* of the curved pitman *G*, and on the other side by a hooked stirrup, *h*, to a coiled spring, *H*, the other end 75 of which is connected by the hook or eye *i* to the outer or free end of a stiff spring, *I*.

The upper end of the curved and jointed pitman *G' G* projects up through a slot, *g*, in the floor of the cab, in which works the treadle *K*, 80 to the lower short arm of which it is hinged, as shown more clearly in Fig. 3 of the drawings.

From the foregoing description, taken in connection with the drawings, the operation of my 85 invention will readily be understood. The fireman, holding the shovelful of coal in both hands, places his foot on the treadle, which swings the door open, and after discharging the shovel into the furnace the door is immediately closed by the operation of the compound springs *I* and *H* and the lever mechanism connecting them with the treadle *K* and pintle *D*, and held closed until again purposely opened by the spring-latch *d e*. In this manner no time is lost in opening and closing the door, which remains open at each firing only long enough to enable the fireman to discharge his shovelful of coal into the furnace, thus saving fuel, as well as time and labor. All the 90 95 100

parts, with the exception of the treadle, are located below the floor of the cab, where they are out of the way, and do not in the least encroach upon or interfere with the working of the engine.

Though intended chiefly for locomotives, it is obvious that my invention is applicable also to the furnace-doors of steamboat-boilers and boilers of marine and stationary engines, in which cases some modification in the arrangement of the operating parts may sometimes be found desirable, without, however, deviating from the spirit of my invention.

I claim and desire to secure by Letters Patent of the United States—

The combination, with a furnace-door, C, and its vertical pintle D, working in boxes e, and provided with the links f, of the connecting rod or arm E, lever F, jointed pitman G/G, treadle K, and compound springs H I, substantially as and for the purpose herein shown and specified.

In testimony that I claim the foregoing as my own I have hereunto affixed my signature in presence of two witnesses.

CASWELL T. CHESHIER.

Witnesses:

LORENZO RACE,

AUGUSTUS J. PARTCH.
